FILLER TOBACCO FEED

Frederick C. Gladeck, Philadelphia, Pa., assignor
to International Cigar Machinery Company, a
corporation of New Jersey

Application April 1, 1942, Serial No. 437,250

22 Claims. (Cl. 131—81)

This invention relates to cigar machines, more particularly to long filler tobacco feeds.

One of the main objects of the invention is to provide a filler feed wherein the tobacco leaves may be laid in a single layer upon a traveling surface which deposits them in an overlapping shingled relationship upon a conveyor which advances the stream so formed to a bunch cutter. Thus the somewhat laborious manual operation of building up a shingled layer of long filler tobacco upon the cross-feed belt of the type of cigar machine shown in the Bronander Patent No. 1,740,571, may be dispensed with.

A further object is to advance the layer of tobacco leaves upon the conveyor while it is traveling through a channel-shaped member whereby the leaves are curled upon themselves. Thus a stream of filler tobacco consisting of curled-up tobacco leaves assembled in overlapping shingled relationship upon the conveyor will be produced and from this stream cigar bunches having a superior draft to those formed by the type of machine shown in the above mentioned Bronander patent will be produced.

Still another object of the invention is to compress the tobacco stream as it emerges from the conveyor in order to give it sufficient body to permit the charges separated therefrom to be transferred to binder applying position without disintegration. In case the tobacco leaves are curled up upon themselves on the conveyor as mentioned above, this is of particular advantage as the curled nature of the separated bunch charges will be retained during transfer to binder applying position. In one form of construction exemplified in the present disclosure for obtaining this compression of the tobacco stream, which is an alternative embodiment, a tapered forming member is employed to produce the requisite compression of the tobacco stream. With these and other objects not specifically mentioned in view, the invention consists in the particular combinations, construction and features hereinafter fully described.

In the accompanying drawings which form a part of this specification:

Fig. 1 is a plan view of the automatic long filler tobacco feed, the knife mechanism being omitted from this view;

Fig. 2 is a side elevation of the improved tobacco feed;

Fig. 3 is a partial end elevation of the tobacco feed showing driving means from line 3—3 of Fig. 1;

Fig. 4 is a sectional view showing the forward- 55

ing belts and knife mechanism, taken along line 4—4 of Fig. 1;

Fig. 5 is a partial plan view of a modified automatic long filler tobacco feed;

Fig. 5A is a detail sectional view on an enlarged scale taken on the line 5A—5A of Fig. 6;

Fig. 6 is a side view of Fig. 5;

Fig. 7 is an end view of the charge transfer mechanism taken from line 7—7 of Fig. 6; and

Fig. 8 is a fragmentary plan view on an enlarged scale of the charge transfer shown in Fig. 7.

Referring to Figs. 1, 2, 3 and 4, the preferred form of automatic long filler tobacco feed consists of pedestals 10 and 12 mounted on the bed of the cigar machine, a bracket 14 being attached to and overhanging said pedestals and supporting a portion of the driving means which will be presently described. An upright frame 15 having legs 16 and 17 fastened to the top of bracket 14 is provided with a vertical slide-way 18 wherein is slidably mounted (Fig. 1) the holder 19 which supports the corrugated cutter 20. On the brackets 22 fastened to the backs of the legs 16 and 17 are mounted rollers 23a and 23b which guide and support the compressing belt 24 which extends between the legs 16 and 17 of frame 15.

The filler tobacco, which is preferably stemmed leaf tobacco, is progressively placed on the intermittently driven horizontal belt 26, by the operator with the lengths of the tobacco leaves extending transversely of the belt in a manner to completely cover the belt. The upper run of belt 26, which is supported by a plate 27 (Fig. 4), advances the tobacco under the lower run of a belt 28 which tends to flatten the leaves and also aids in conveying the same into the portion of the feed belt 32 which runs through and is thereby folded upwardly within a channel 30 (Fig. 4) 40 within the U-shaped forming block 34.

Belt 32 travels in a transverse direction to belt 26 and is intermittently driven. The belt 32 derives intermittent motion from a shaft 36, Figs. 1, 2 and 3, which is carried by the pedestals 10 and 12, shaft 36 being provided with a sprocket 38 driven by a chain 40 running over a sprocket (not shown) mounted on a continuously driven shaft of the cigar machine. A crank arm 42 fastened to the end of shaft 36 protruding from pedestal 10 is provided with a stud 44 engaging in an elongated slot 46 of a link 48, the latter being connected to an arm 50 loosely mounted on a shaft 52 supported by pedestal 10 and bracket 73 (Fig. 2). The upper end of arm 50 is provided with a stud 54 supporting a pawl

56 engaging a ratchet wheel 58 fastened on shaft 52, whereby the latter is driven during the counter-clockwise movement of the pawl when the stud 44 engages the outer end of slot 46 while moving in a counter-clockwise direction. Thus the belt 32, which is driven from shaft 52 as will be presently described, is intermittently driven during the counter-clockwise movement of the pawl, the latter movement being limited when the pawl engages a stop pin 60 (Fig. 3). A stop screw 62 mounted on the link 48 is engaged by the stud to return the pawl to initial position, and the lost motion of the stud 44 in the slot 46 may be varied by adjustment of the screw 62, whereby the initial position of the pawl may be varied to permit adjustment of the feeding stroke of the pawl. An adjustable screw 64 is secured in a strap 66 suspended from the machine to limit the travel of pawl 56 in the rearward direction.

The turning of shaft 52 imparts motion to a bevel gear 68 in mesh with a bevel gear 70 mounted on a vertical shaft 72 which is supported by the bracket 73. The upper end of shaft 72 passes through a hole in a boss formed on the inner end of the depressed cross web 74 of the bracket 14 (Figs. 1 and 2), and the portion of this shaft below web 74 is equipped with a bevel gear 75 in mesh with a bevel gear 76 mounted on a horizontal shaft 78 supported in bracket 14, the shaft 78 also carrying a spur gear 80 in mesh with a spur gear 82 mounted on a shaft 84 supported by bracket 14. Shaft 84 is provided with a drum 86 driving the belt 32 which runs over idler pulleys 88 and 90, whose spindles are removably mounted in recesses 91 formed in the vertical walls 95 connecting the top of bracket 14 to the depressed web 74, and pulleys 94, 96, 98 and 99. The projecting ends of the shaft of the pulley 99 are supported in notches of the bracket 100 fastened to the outer side of bracket 14, and the ends of the roller 99 may be tapered as shown in Fig. 1. The belt 32 extends between the legs 16 and 17 of frame 15, and the upper run thereof from the roller 88 to the legs 16 and 17 is supported by a plate 97 fastened to the top of bracket 14. The gear 82 protrudes through a slot 87 in the top of the bracket 14 and meshes with and drives a gear 101 mounted on a shaft 102 journaled in the legs 16 and 17 of the frame 18, said shaft also having a pulley 104 driving the compressing belt 24 which runs over the idler pulleys 23a, 23b and 23c. The ends of the shaft of roller 23c are removably mounted in notches in lugs 105 projecting from the front of the legs 16 and 17 and retained therein by plates 106 fastened to the lugs 105. The end of the shaft of the roller 23a are also removably mounted in recesses in the brackets 22 and secured therein by plates 106a.

The shaft 36, Figs. 1 and 3, is provided with a sprocket 107 driving a chain 108 running over a sprocket 110 mounted on a shaft 112 supported by pedestals 10 and 12. The end of shaft 112 is provided with a crank arm 114 having a stud 116 engaging in an elongated slot 118 of a link 120, the latter being connected to an arm 122 fastened on a shaft 124 supported by a bracket 126 fastened to the top of bracket 14, as seen in Fig. 1. The outer end of arm 122 is equipped with a stud 128 supporting a pawl 130 engaging a ratchet wheel 132 loosely mounted on shaft 124. A gear 134 which is secured to the ratchet wheel 132 (Fig. 3) is engaged by a cap screw 135 threaded into shaft 124 which serves to retain the ratchet against the hub of arm 122. The gear 134 drives

a gear 136 which is in mesh with a gear 138 (Figs. 1, 3 and 4), thereby driving the belts 26 and 28. The gear 136 is mounted on a shaft 140 supported by lugs 142 extending from member 34, said shaft 5 also carrying a pulley 144 driving the belt 26 which runs over an idler pulley 146. Gear 138 is mounted on a shaft 148 supported by lugs 150 extending from a guide bracket 152 secured to member 34, this shaft carrying a pulley 154 driving the belt 28 running over an idler pulley 156 mounted on a stationary shaft 158.

When the stud 116 engages the outer end of slot 118 while traveling in a counter-clockwise direction, the pawl 130 drives the ratchet 132. 15 While the stud 116 travels inwardly from the outer end of the slot 118 the pawl 130 remains stationary, the further driving movement of pawl 130 being limited by stop 160. This is the position of the pawl 130 shown in Fig. 3, the stud 116 moving toward the stop screw 162 on link 120 to engage said screw to return the arm 122 with the pawl 130 to initial position. At the same time the stud 44 engages the outer end of slot 46 to drive the pawl 56 forwardly and thereby advance the belt 32. While the pawl 130 is driving the ratchet forwardly in a counter-clockwise direction, the belts 26 and 28 will be driven, but the driving thereof is interrupted when the pawl engages a stop pin 160. By adjusting stop screw 30 162 on link 120 the lost motion of the stud 116 in the slot 118 may be varied, and thus the pawl 130 will be returned to a different initial position and its feeding stroke will be varied. An adjustable screw 164 is secured in the tail 166 of arm 122 (Fig. 3) and adapted to engage a bracket 168 fastened to pedestal 10, to limit the travel of arm 122 in the rearward direction.

A sprocket 170, Fig. 3, mounted on shaft 112 drives a chain 172 running over a sprocket 174 mounted on a sleeve 176 turning on the shaft 158. A cam 178, Figs. 1 and 4, mounted on sleeve 176 engages a cam roller 180 carried by a cam lever 182 mounted on a pivot 184 supported in the bracket 186 which also supports shaft 158, the bracket 186 being supported by a suitable portion of the frame of the machine, not shown. The other end of cam lever 182 supports one end of a link 188 connected to the projecting lug 190 of a slide 192 operating in a slideway 194 provided in bracket 186. A knife 196 carried by slide 192 and guided in a slot 198 of member 152 is provided to sever the filler tobacco overlying the ledger plate 200 secured to member 34. The severing operation is accomplished when the high portion 202 of the cam engages the cam roller 180 which happens at a time when the belts 26, 28 and 32 are not in motion. A tension spring 204 anchored to bracket 186 is provided to hold cam roller 180 in engagement with the cam 178.

60 The operation of the filler feed will now be described:

The operator places the filler tobacco upon belt 26 to form a continuous layer, preferably with the lengths of the filler leaves extending transversely of the belt, and the filler tobacco will be advanced towards the channel 30 when motion is imparted to the belts 26 and 28. It will be understood that when belts 26 and 28 receive motion, the driving of belt 32, which runs in channel 30 will be interrupted. Thus the filler tobacco will be advanced over the ledger plate 200. The belts 26 and 28 may be advanced sufficiently upon appropriate adjustment of the stop screw 162 on link 120 (Fig. 3) to cause the leading end of the layer of filler tobacco passing over

plate 200 to engage the U-shaped channel portion 30 of belt 32 and curl upon itself. However, the stop screw 162 may be adjusted to diminish the extent the belts are advanced, so that the leading end of the layer will not be curled upon itself but will merely assume the contour of the bottom of the channel portion 30 of said belt.

Preferably the leaves are overlapped on the belt 26, as shown in Fig. 1, so that the curling of the leading end of the layer L in channel 30 will be assured. When the drive of belts 26 and 28 is stopped and before the travel of belt 32 is resumed, the knife 196 by means of its cam is actuated to sever the filler tobacco overhanging the ledger plate 200. The knife having accomplished its duty then returns to its up-position and motion will be imparted to belt 32 to advance the column of filler tobacco in the channel 30 a distance corresponding to the length required for one cigar bunch, and said belt will again be stopped. At this time the belts 26 and 28 will again be driven and the additional section of filler tobacco so advanced will partially overlap the previously severed tobacco section deposited on belt 32. The belts 26 and 28 are made comparatively wide so that they can supply tobacco to channel 30 a number of times before the section of the column of tobacco within said channel advances beyond their range. It will be seen that a continuous column or layer of filler tobacco is thus built up in a layer by layer fashion, or shingled relationship, resulting in a more even distribution of the tobacco and thereby eliminating the possibilities of a hollow portion forming in the column.

As the belt 32 emerges from the former block 34, Fig. 1, it spreads outward as it passes beyond pulley 88 and returns to a flat or outspread condition, and this shape is retained until it runs over pulley 98 whereupon the belt is again folded upwardly within the former block. The opening of belt 32 permits the tobacco column to spread out, and in being advanced under the belt 24 it is compressed to give it sufficient density to be advanced over the ledger plate 200a without disturbance, such as "telescoping," into position for severance of a bunch length by the corrugated cutter 20. The corrugated cutter 20 which is of well known construction as shown in the patent to Bronander 1,740,571, descends and severs a bunch length having notched or pigtail ends, and the column of tobacco in the bunch length may be sufficient for one cigar bunch, the severed length then being transferred to a bunch rolling apron for application of a binder thereto.

In the modified form of automatic filler tobacco feed disclosed in Figs. 5, 6 and 7, the operator places the filler tobacco upon belt 26a, and the same is conveyed between belts 26a and 28a to the belt 32a in the same manner as heretofore described. The driving of belts 26a, 28a, and 32a is also controlled in the same manner as previously described, and the belt 32a passes through a hollow former block 34a which similarly folds the belt 32a to form a channel into which the leading end of the tobacco layer is advanced from between belts 26a and 28a and then severed. As the belt 32a emerges from the former block 34a, Fig. 5, it spreads outwardly in the same manner as heretofore related, but in this arrangement the tobacco column enters into a forming member 210 of U-shaped cross-section supported from the bracket 14a which is carried by the pedestals 10a and 12a in the same

manner as shown in Figs. 1-4. Thus the column of tobacco will be kept in its pre-formed condition. It will be seen that the end of member 210, adjacent member 34a is considerably larger than at its outlet end 212, Fig. 5, this tapering of member 210 causing the tobacco to be pressed together into the form of a somewhat cylindrically shaped column. Since the member 210 is open at its bottom, the tobacco column will be carried through it on the belt 32a and thereby gradually compacted to a breadth narrow enough to enter the pocket 214 hereinafter described.

The upper run of the belt 32a is guided under the member 210 by rollers 88a and 99a. The ends of the shafts of rollers 88a and 99a may be removably mounted in indentations 91a in the vertical walls 95a connecting the top of the bracket 14a to a cross web 74a similar to the cross web 74 shown in Figs. 1 and 2. The ends of the shaft of roller 99a are supported in notches of bracket 100a fastened to the front of the bracket 14a. The portion of the upper run of belt 32a between rollers 88a and 99a may be supported by a plate similar to the plate 97 shown in Figs. 1 and 2. The belt 32a is guided by rollers 90a and 94a and by rollers (not shown) similar to the rollers 96 and 98 in Fig. 2 and is driven by a drum 86a mounted on a shaft 84a supported in the bracket 14a and provided with a gear 82a driven from a gear 80a on a shaft 78a carrying a bevel gear 76a driven from a bevel gear 75a on a vertical shaft 72a which is supported in a bracket 73a and passes upwardly into a hole in cross web 74a. The bevel gear 70a on the lower end of shaft 72a is driven from the bevel gear 68a on shaft 52a. Since the construction of this gear train for driving the drum 86a is similar to that for driving the drum 86 in Figs. 1-4, and the construction of the pawl-and-ratchet-mechanisms 40 for driving the shaft 52a and the pulleys 142a and 150a of the belts 26a and 28a, is the same as that shown in Fig. 3, further description thereof is deemed unnecessary. However it will be noted that the sections of tobacco advanced into the former 34a by the belts 26a and 28a will be severed by a knife (not shown) actuated by mechanism controlled from a cam (not shown) mounted on a sleeve (not shown) supported on shaft 158a and similar to that shown in Fig. 4. The tobacco column on leaving belt 32a passes over a ledger plate 213 and enters into a U-shaped pocket 214, Figs. 7 and 8, the portion of the tobacco column behind the pocket being severed by a suitable corrugated cutter 216 which descends and thus severs the bunch-length charge from the remainder of the tobacco column.

The forming member 210 is supported by cross bars 218 having spacers 220 which rest on the bracket 14a. The pocket 214 is slidably fitted within a U-shaped guide 222 which is supported by a holder 224 attached to bracket 14a as shown in Fig. 5. The pocket 214 is attached to a rod 226 which at its lower end carries a pin 228 engaging in a slot 230 of a cam lever 232 loosely mounted on a shaft 234 fastened in a boss 236, Fig. 6, carried by frame 12a. The opposite end of cam lever 232 is provided with a cam roller 238 engaging in a track 240 of a cam 242 fastened on a shaft 244. Shaft 244 corresponds to the shaft 36 shown in Fig. 2, the only difference being that in the present arrangement the shaft 244 protrudes from pedestal 12a to carry cam 242.

A rod 246, Fig. 7, is provided to open the trans-

fer fingers 248 and 250, this rod being operated by a cam lever 252 mounted on a pivot stud 254 carried by an arm 256 fastened to and suspended from shaft 234. The lever 252 is provided with a cam roller 258 which engages the periphery of cam 242. The cam 242 is provided with a high portion 260 adapted to engage roller 258, thus actuating cam lever 252 and causing rod 246 to move upward and engage a lug 262 extending from finger 248 and thereby swinging the fingers from their closed to open position in readiness to receive the charge C.

With the charge C lodged in pocket 214, the rod 246 is raised and swings the fingers 248 and 250 to their open position as shown in dotted lines, whereupon the cam actuated rod 226 is raised to elevate the pocket 214 and thereby bringing the charge C into the space between said transfer fingers. The pocket 214 retains this position and rod 246 is returned to its lower position as roller 258 rides off cam surface 260. A compression spring 264 located on and abutting against a collar on the lower portion of rod 246 tends to hold said rod in engagement with cam lever 252 and thereby holds cam roller 258 in engagement with cam 242. The descent of rod 246 permits the transfer fingers 248 and 250 to return to their closed position as will be presently described, and grip the charge C. The fingers are provided with prongs 265 which in closing pass through the slots 266, which are provided in the sides of pocket 214, and thereby grasp the charge. The pocket then descends, permitting the transfer to carry the charge C to the bunch rolling apron for application of a bunch to the charge.

The guide 222 is provided with spaced ribs 268 fitting into the slots 266 of pocket 214, said ribs being shaped to conform with the shape of the side walls of the pocket and in this manner prevents the charge from being disarranged when conveyed into said pocket. The pocket 214 slides on ribs 268 while descending from the fingers 248 and 250.

The transfer fingers 248 and 250 at their upper ends are provided with intermeshing gear segments 270 which serve to open and close the finger 250 simultaneously with finger 248. As previously related the rod 246 serves to open the fingers, and when said rod descends, a tension spring 272 stretched across the fingers will cause the same to return to their closed position. A stop screw 274 carried by finger 250 is provided to engage the finger 248 and prevent unnecessary squeezing of the charge. The fingers 248 and 250 are carried by an arm 216 which is part of a suitable charge transfer which may be suitably operated to transfer the charge C to the bunch rolling apron for rolling in a binder to form a bunch.

What is claimed is:

1. In a cigar machine, the combination with a conveyor adapted to advance a continuous stream of long filler tobacco, of mechanism for separating tobacco sections from one end of a layer of tobacco leaves whose lengths extend transversely of the length of said layer and assembling the separated sections in shingled relationship upon said conveyor to form a continuous stream of tobacco leaves thereon whose lengths extend lengthwise of the conveyor, and mechanism for separating from the leading end of said stream lengths of filler tobacco whose lengths correspond to the desired length of bunch charge and transferring the separated lengths to a predetermined position.

2. In a cigar machine, the combination with a

conveyor adapted to advance a continuous stream of long filler tobacco, of mechanism for separating tobacco sections from one end of a layer of tobacco leaves whose lengths extend transversely of the length of said layer and assembling the separated sections in shingled relationship upon said conveyor to form a continuous stream of tobacco leaves thereon whose lengths extend lengthwise of the conveyor, mechanism for separating from the leading end of said stream lengths of filler tobacco whose lengths correspond to the desired length of bunch charge and transferring the separated lengths to a predetermined position, and means for driving said conveyor, said means being adjustable to advance said stream by various increments corresponding to various desired lengths of bunch charges.

3. In a cigar machine, the combination with a conveyor adapted to advance a continuous stream of tobacco intermittently, of mechanism for separating tobacco sections from one end of a continuous layer of tobacco leaves and assembling the separated sections upon said conveyor to form a continuous stream of tobacco thereon with the lengths of the leaves extending lengthwise of the conveyor, a corrugated cutter for separating a bunch length having notched ends from the leading end of the stream during an interval while the stream is not being advanced, and a device for transferring the severed bunch length to a predetermined position.

4. In a cigar machine, the combination with an endless conveyor adapted to feed a continuous stream of filler tobacco, of mechanism for advancing a layer of filler tobacco to advance a section thereof on to said conveyor, and a device for subsequently separating the section of said layer so advanced on to the conveyor, said mechanism and device being operated in properly timed relation to the movement of said conveyor to advance said layer and separate the sections thereof advanced on said conveyor to form a continuous stream of filler tobacco on the latter.

5. In a cigar machine, the combination with a conveyor adapted to feed a continuous stream of filler tobacco, of a channel-shaped member through which said conveyor passes, mechanism for advancing a layer of filler tobacco transversely of said conveyor into the channel of said member, whereby the leading end of said layer is curled upon itself within said channel and advanced upon the conveyor, and a device for severing the section of said layer constituting the curled end thereof, said mechanism and device being operated in properly timed relationship to the movement of said conveyor to assemble the severed sections on the conveyor to form a continuous stream of filler tobacco thereon.

6. In a cigar machine, the combination with a conveyor adapted to feed a continuous stream of filler tobacco, of a channel-shaped member through which said conveyor passes, mechanism for advancing a layer of filler tobacco transversely of said conveyor into the channel of said member, whereby the leading end of said layer is curled upon itself within said channel and advanced upon the conveyor, a device for severing the section of said layer constituting the curled end thereof, said mechanism and device being operated in properly timed relationship to the movement of said conveyor to assemble the severed sections on the conveyor to form a continuous stream of filler tobacco thereon, and means for driving said conveyor in properly timed

relationship to said mechanism to cause overlapping of said severed sections in shingled relationship on said conveyor.

7. In a cigar machine, the combination with a conveyor adapted to feed a continuous stream of filler tobacco, of a channel-shaped member through which said conveyor passes, mechanism for advancing a layer of filler tobacco transversely of said conveyor into the channel of said member, whereby the leading end of said layer is curled upon itself within said channel and advanced upon the conveyor, a device for severing the section of said layer constituting the curled end thereof, said mechanism and device being operated in properly timed relationship to the movement of said conveyor to assemble the severed sections on the conveyor to form a continuous stream of filler tobacco thereon, and means for separating bunch lengths from the leading end of said stream.

8. In a cigar machine, the combination with a conveyor adapted to feed a continuous stream of filler tobacco, of a channel-shaped member through which said conveyor passes, mechanism for advancing a layer of filler tobacco transversely of said conveyor into the channel of said member, whereby the leading end of said layer is curled upon itself within said channel and advanced upon the conveyor, a device for severing the section of said layer constituting the curled end thereof, said mechanism and device being operated in properly timed relationship to the movement of said conveyor to assemble the severed sections on the conveyor to form a continuous stream of filler tobacco thereon, means for driving said conveyor in properly timed relationship to said mechanism to cause overlapping of said severed sections in shingled relationship on said conveyor, and devices for separating bunch lengths from the leading end of said stream.

9. In a cigar machine filler feed, the combination with a traveling apron for feeding a broad thin layer of long filler tobacco, of cross feed conveyor means traveling transversely of said apron adjacent one edge thereof in position to receive filler tobacco delivered from said apron, means for periodically severing a tobacco section from the delivery edge of said broad thin layer along a line parallel with the direction of movement of said cross feed conveyor, at a distance behind said delivery edge approximately the thickness of a bunch, to successively assemble the severed sections on said cross feed conveyor in overlapping shingled relationship to form a stream of approximately bunch cross-section, and means cooperating with said cross feed conveyor to cut charges at a distance from the leading end of said stream of approximately the length of a bunch.

10. In a cigar machine, the combination with a conveyor for feeding a continuous stream of filler tobacco, of mechanism for depositing filler tobacco leaves upon said conveyor with the lengths thereof extending lengthwise of the conveyor to form thereon a continuous stream of tobacco whose breadth is approximately the thickness of a bunch charge, and a device for separating bunch length charges from the forward end of said stream, said mechanism operating to deposit the filler tobacco in overlapped shingled relationship on said conveyor, means for adjusting said mechanism to vary the rate at which the filler tobacco is deposited on the conveyor, and drive means for said conveyor, said drive means operating to advance the conveyor by increments corresponding to the desired length of charge to

be separated by said device, and said device including a cutter arranged at a distance from the forward end of said stream corresponding to the desired length of the bunch charges.

5 11. In a cigar machine, the combination with a flexible endless conveyor belt, of mechanism for depositing filler tobacco upon said belt, a member for maintaining said belt in upwardly folded relationship about the filler tobacco deposited thereon, means for compacting the filler tobacco as it emerges from the upwardly folded portion of said belt, and devices for separating bunch lengths from the filler tobacco compacted by said means and transferring the same to a predetermined position.

12. The combination with a conveyor, of means for assembling curled rolls of long filler tobacco in overlapping relationship upon said conveyor to form a continuous stream of tobacco thereon, a hollow member having a tapering opening arranged to admit said stream as it is advanced by said conveyor and thereby compress the same, and a knife for separating bunch length charges from said stream, and mechanism for transferring the separated charges to a predetermined position.

13. In a cigar machine, the combination with a conveyor, of mechanism for depositing long filler tobacco upon said conveyor with the lengths of the tobacco leaves extending lengthwise of said conveyor to form a continuous stream of tobacco thereon, a member arranged to separate tobacco sections from the forward end of said stream, means for advancing said conveyor by increments corresponding to the desired length of bunch charge, whereby sections having a length corresponding to the desired length of bunch charge will be separated from the forward end of the stream, a bunch transfer having

40 opposed fingers adapted to admit a separated bunch length therebetween and grip the same, and a device for transferring each separated bunch length individually to a position between said transfer fingers to be gripped by the latter.

45 14. In a cigar machine filler feed, the combination with a traveling apron for feeding a broad continuous layer of long filler tobacco leaves arranged with lengths of the filler extending transversely of the apron, of a conveyor traveling transversely of said apron adjacent one end thereof in position to receive filler tobacco delivered from said apron and then advance the same with the lengths of the filler tobacco leaves extending lengthwise of said conveyor into position for severance of bunch lengths therefrom, and means for advancing said conveyor by increments corresponding to the desired bunch lengths to be severed from the filler tobacco on said conveyor.

60 15. The combination with a conveyor adapted to feed filler tobacco, of a channel-shaped member through which said conveyor passes, and mechanism for advancing a layer of filler tobacco transversely of said conveyor into the channel of said member whereby the filler tobacco is curled upon itself within said member and advanced upon said conveyor.

65 16. The method comprising advancing a stream of long filler tobacco, curling the forward end of the stream upon itself to form a roll of tobacco, separating the roll so formed from the stream, advancing the separated roll lengthwise, advancing said stream to a position wherein it overlaps the separated roll and curling the forward end of said stream upon itself

to form a second tobacco roll and separating the roll so formed from the stream, and then advancing lengthwise the overlapped rolls of tobacco so produced and advancing said stream upon the second roll, and repeating the curling of the forward end of the stream and the separation of a roll therefrom.

17. The method comprising advancing a broad thin layer of long filler tobacco, wherein the lengths of the filler tobacco extend transversely of said layer, on to a conveyor moving transversely of said layer, separating sections from the forward edge of said layer to form a continuous stream of tobacco on said conveyor with the lengths of the filler tobacco extending lengthwise of the conveyor, and separating bunch lengths from the forward end of said stream at a distance from the forward end of said stream corresponding to the desired length of bunch charge.

18. In a cigar machine, the combination with an endless conveyor adapted to feed a continuous stream of filler tobacco, of mechanism for advancing a layer of filler tobacco to advance a section thereof on to said conveyor, and a device for subsequently separating the section of said layer so advanced on to the conveyor, said mechanism and device being operated in properly timed relation to the movement of said conveyor to advance said layer and separate the sections thereof advanced on said conveyor to form a continuous stream of filler tobacco on the latter, and means for driving said conveyor in properly timed relationship to said mechanism to cause overlapping of said sections in shingled relationship upon said conveyor.

19. In a cigar machine, the combination with an endless conveyor adapted to feed a continuous stream of filler tobacco, of mechanism for advancing a layer of filler tobacco to advance a section thereof on to said conveyor, and a device for separating the section of said layer so advanced on to the conveyor, said mechanism and device being operated in properly timed relation to the movement of said conveyor to advance said layer and separate the sections thereof advanced on said conveyor to form a continuous stream of filler tobacco on the latter, and a device for separating from the forward end of said stream lengths of filler tobacco whose lengths correspond to the desired length of bunch charge and transferring them to a predetermined position.

20. In a cigar machine, the combination with an endless conveyor adapted to feed a continuous stream of filler tobacco, of mechanism for feeding a layer of filler tobacco transversely of said conveyor on to the latter to advance a section of said layer on to said conveyor, a device for subsequently separating the section of said layer so advanced upon the conveyor, said mechanism and device being operated in properly timed relationship to advance said layer and separate the sections thereof advanced on said conveyor to form a continuous stream of filler tobacco on said conveyor.

21. In a cigar machine, the combination with an endless conveyor adapted to feed a continuous stream of filler tobacco, of mechanism for feeding a layer of filler tobacco transversely of said conveyor on to the latter to advance a section of said layer on to said conveyor, a device for subsequently separating the section of said layer so advanced upon the conveyor, said mechanism and device being operated in properly timed relationship to advance said layer and separate the sections thereof advanced on said conveyor to form a continuous stream of filler tobacco on said conveyor.

22. In a cigar machine, the combination with a conveyor for intermittently feeding a continuous stream of filler tobacco, of mechanism for depositing filler tobacco leaves upon said conveyor with the lengths thereof extending lengthwise of the conveyor to form thereon a continuous stream of tobacco whose breadth is approximately the thickness of a bunch charge, and a device for separating bunch length charges from the forward end of said stream during intervals while the said stream is not being fed, said mechanism operating to deposit the filler tobacco in overlapped shingled relationship on said conveyor, and means for transferring the separated bunch length charges individually to a predetermined position, said device including a cutter arranged at a distance from the forward end of said stream corresponding to the desired length of the charges.

FREDERICK C. GLADECK.
